BLASTING CONTROL

Richard N. Snyder, Springfield, Va., assignor to Safety
Devices, Inc., Springfield, Va.

Filed Mar. 20, 1973, Ser. No. 342,950

Term of patent 14 years

Int. Cl. D13—03

U.S. Cl. D26—13 R

The figure is a plan view of a blasting control, showing my new design.

The undisclosed sides are planar and unornamented.

The broken lines are for illustrative purposes only.

I claim:

The ornamental design for a blasting control, as shown and described.
